ROTARY PUMP

Application filed November 28, 1928. Serial No. 322,423.

This invention relates to improvements in rotary pumps.

The primary object of this invention is the provision of a rotary pump by means of which water or other liquid may be elevated from a low to a higher level, without the use of valves and like expedients, and discharged in a stream facing in a predetermined direction.

Other objects and advantages of this invention will be apparent during the course of the following detailed description.

In the accompanying drawing, forming a part of this specification, and wherein similar reference characters designate corresponding parts throughout the several views.

Figure 1 is a fragmentary side elevation, partly in section, of the improved pump.

Figure 2 is a horizontal sectional view taken through the pump substantially on the line 2-2 of Figure 1.

In the drawing, wherein for the purpose of illustration is shown only a preferred embodiment of the invention the letter A may generally designate the improved pump, which includes a frame B connected in a stationary relation to a support C, and rotatably supporting a pump D which discharges water into a preferably stationary outlet E.

The support C may be a beam, floor, or other type of support, and it is provided with a suitable collar 10, to which the uprights 12 of the frame B are connected, as shown at 13. The uprights 12 are four in number, spaced 90° apart, but they may be of any approved number, and the frame may be otherwise formed. The uprights 12 extend from the collar 10 in depending parallel relation for their major length, and at the lower ends thereof the same are bowed outwardly

at 15, in an opposed divergent relation. The diametrically opposed uprights 12 at their extreme lower ends are bent at 16, inwardly, and connected by horizontal portions 17 and 18, which are in right angled relation and cross each other in an intersecting relation with the axis of the rotary pump D. The uprights 12 at their upper ends extend above the collar 10 and are bowed inwardly at 21, to support a bearing 22, as by detachable bolts 23.

The pump D preferably comprises the pref-

erably vertically disposed body conduit 30, the walls of which are preferably straight, but may be tapered to enable a better centrifugal action, if found necessary. The conduit body 30 extends vertically through the frame B between the spaced uprights 12 of said frame, and it extends upwardly thru the bearing 22 to a point thereabove. The top frame bearing 22 is preferably anti-friction, including rollers 32, and this bearing, in fact, is ring-shaped, and supporting the rollers 32 in an annular relation so that the external periphery of the conduit 30 will abut in bearing relation thereagainst, as is shown in Figure 1 of the drawings, to permit a free rotation of said conduit.

At the lower ends of the uprights 12, preferably where the portions 15 of the uprights bow in a divergent relation, is disposed a bearing 36, bolted or riveted at 37 to the uprights 12, and which includes a ring-shaped body having an annular arrangement of anti-friction rollers 39, thru which the lower end of the conduit 30 extends in a bearing relation thereagainst. An intermediate ring-shaped bearing 40, is bolted or riveted at 41 to the uprights 12, at a location about midway between the bearings 22 and 36, and the same provides an opening having an arrangement of anti-friction rollers or bearings 43 therein, thru which and against which the conduit 30 extends, in a rotary bearing relation, as shown in Figure 1.

At its upper end, above the bearing 22, the conduit 30 is provided with means to drive the same, which may be gearing, but is preferably a pulley wheel 50 keyed therewith, having a belt 51 trained thereover and leading to any desired prime mover.

At its lower end the conduit 30 is provided with diametrically opposed intake extensions 55 and 56, which extend substantially radial from the conduit 30, but slope with their axes inclined to a plane normal to the axis of the conduit 30, so as to more readily catch the water or fluid being pumped, and force the column upwardly through the conduit 30. These intake extensions 55 and 56 are arcuated with their concave sides facing in the direction of rotation. At their en-

trance ends they are flared outwardly with enlarged mouths, and the plane of the edges of the mouths of the intake extensions incline to the vertical, to provide a sort of lip portion at the top of the flared mouths, to more readily scoop the water into the extensions, as can easily be seen from Figure 2 of the drawings in full and dotted lines at the entrance edges of the intake extensions. If desired, more than two of the intake extensions may be provided.

Axially of the conduit D, at the juncture of the portions 55 and 56, is provided a step bearing 60, preferably anti-friction, supported at the location where the horizontal portions 17 and 18 of the frames cross each other, as shown in Figure 1 of the drawing. This receives the end thrust of the pump.

The discharge or outlet is preferably of elbow formation, comprising a relatively large conduit 70, connected by a bend 71 with a portion 72. The portion 72 is adapted to be vertically disposed and connected by a swivel 73 with the upper end of the conduit 30. This swivel 73 may be of the type shown, or it may be of the anti-friction variety, provided with any approved means to prevent leakage of the liquid thereby. In the illustrated instance, a flanged ring 75 is screw threaded on the top of the conduit 30, and a nut 75^a connects the portion 72 of the outlet thereto; the nut 75^a being screw threaded on the portion 72. The bend 71 is of such nature that the portion 70 of the outlet is disposed on a downward slant to the horizontal, and at its free end may have a connection 78 which will permit its attachment to tubing, or the like. The outlet E is supported by a bracket 80 carried by the support C, so that the outlet or discharge connection is not rotatable with the pump, but held stationary and discharges the stream in one direction, either into a receptacle, or suitable hose or a conduit system.

The operation of the invention will be apparent from the foregoing. Through the belt 51, or analogous means, the conduit 30 is rotated, and the intake conduit extensions at the lower ends thereof will be swirled in the body of water, and due to the flared entrance ends of these intake extensions, their downward inclination and their arcuated formation, the water will be directed with considerable power into the conduit 30 for lifting the column of water therein, which is assisted to some extent by centrifugal force; the column of water being discharged upwardly into the outlet E, and to any desired location.

In order to prevent a whirlpool effect in the water adjacent the intake extensions, such as would defeat the purpose of the invention, it is preferred to place fins 85, or like obstructions on the frame B immediately above the intake extensions 55 and 56, which extend substantially radial to the conduit 30 from a location inwardly of the ring-shaped travel

of the entrance ends of the intake extensions to a location outside of such ring, as can readily be understood from Figure 1 of the drawings. These fins 85 are of plate formation, flanged at 87 and 88 for respective attachment, as by bolts or rivets, to the frame portions 15 and the bearing 36.

From the foregoing description of this invention it is apparent that an improved rotary pump has been provided, which is relatively simple, and which enables an efficient pumping of water or like fluid from a low to a high level, without valves, and discharging it in a stream of water facing in a predetermined direction.

Various changes in the shape, size, and arrangement of parts may be made to the form of invention herein shown and described, without departing from the spirit of the invention or the scope of the claims.

We claim:

1. A rotary pump, comprising a vertical open framework enlarged at its lower end to provide a base portion, a vertically disposed pipe mounted in bearings in the framework to turn therein, means for rotating the pipe, a stationary take-off connection coupled to the upper end of the pipe, a step bearing in the base portion of the framework for supporting the pipe, and a pair of intake extensions flaring radially from the lower end of the pipe in said base portion of the framework and being turned and opening in the direction of rotation of the pipe.

2. A rotary pump, comprising a vertical open framework enlarged at its lower end to provide a base portion, a vertically disposed pipe mounted in bearings in the framework to turn therein, means for rotating the pipe, a stationary take-off connection coupled to the upper end of the pipe, a step bearing in the base portion of the framework for supporting the pipe, a pair of intake extensions flaring radially from the lower end of the pipe in said base portion of the framework and being turned and opening in the direction of rotation of the pipe, and stationary fins mounted on said base portion radially of the pipe and disposed immediately above the intake extensions and extending outwardly beyond the open ends thereof.
